INSERT PUMPNorbert N. Knabe, John A. Knabe, and Thomas J. Knabe, all of Rte. 1, Muenster, Tex.
Filed July 5, 1957, Ser. No. 670,246
2 Claims. (Cl. 103—155)

This invention relates to improvements in oil well pumping apparatus and more particularly, but not by way of limitation, to an attachment for utilization with a reciprocating type insert pump.

Many producing oil wells today are provided with reciprocating insert pumps disposed in the lower portion of the oil well tubing in order to move or elevate the oil from the oil reservoir at the bottom of the well bore to the surface of the ground. Many of the fluid reservoirs contain oil contaminated with sand and other abrasive particles that are very detrimental to the working parts of the reciprocal pump. The abrasive action of the sand, and the like, wears away the sealing members and soon renders the pump inefficient in operation so that it must be pulled from the well tubing and repaired or replaced. It will be apparent that this is a time consuming and expensive process, particularly when it is considered that the pump is often located several thousand feet below the surface of the ground.

The present invention contemplates an attachment for utilization with an insert type pump particularly designed and constructed to direct the oil solution from the fluid reservoir in the well bore into the well tubing for elevation to the surface in such a manner that the oil fluid itself is never brought into contact with the working parts of the pump. Thus, sand and other detrimental foreign particles cannot damage the pump or cause an inefficient operation thereof. The life of the pump is greatly prolonged, and the upkeep and repair thereto is greatly reduced, thereby providing for an economical operation of the pump for producing the oil from the well bore.

It is an important object of this invention to provide a novel attachment for oil well insert pumps in order to move the oil fluid from the well bore into the well tubing for elevating to the surface of the well.

It is another object of this invention to provide a novel attachment for an oil well insert pump so designed and constructed to produce oil from the well bore in a manner to preclude contamination of the pump with sand particles and other abrasive material which may be present in the fluid.

Another object of this invention is to provide an attachment for insert pumps for discharging the oil fluid into the well tubing in a manner to substantially preclude the accumulation of corrosion, and the like, in the inner surface of the well tubing, thereby facilitating the production of oil from the well bore.

And still another object of this invention is to provide an attachment for insert pumps which is simple and efficient in operation and economical and durable in construction.

Other objects and advantages of the invention will be evident from the following detailed description, read in conjunction with the accompanying drawings, which illustrate our invention.

In the drawings:

FIGURE 1 is a broken vertical sectional view of the lower portion of an oil pump attachment embodying the invention and installed in a well tubing.

FIGURE 1A is a broken vertical elevational view partly in section of the upper portion of the attachment shown in FIG. 1.

FIGURE 2 is a side elevational view of a portion of the pump attachment of the invention.

2

Referring to the drawings in detail, reference character 10 indicates the well casing or tubing normally extending throughout the length of a well bore (not shown). The well tubing 10 usually extends downwardly

5 in the well bore to a depth below the top of the oil reservoir (not shown) in order that the oil from the oil bearing formation or oil reservoir may be accumulated by natural flow within the well casing for elevation therefrom to the surface of the ground. A standing valve, 10 generally indicated at 12, and having a longitudinal bore 14 extending therethrough, is usually disposed in the proximity of the lower end of the tubing 10 and extends downwardly within the casing to a position below the surface of the oil reservoir so that the lower end of the bore 14 is in communication with the oil or fluid accumulated in the casing. A plurality of suitable annular sealing cups 16 are provided on the outer periphery of the standing valve 12 for sealing against the inner periphery of the tubing 10 and function to retain the standing valve 12 securely therein. The upper portion of the valve 12 is provided with a suitable valve seat insert member 18 for receiving a ball valve member 20 which rests on the valve seat portion 18 in a normally closed position for the valve.

25 A sleeve or tubular housing member 22 is threadedly connected at 24 to the standing valve 12 and extends upwardly therefrom to encase the ball valve 20 and seat 18, and provides a chamber 26 thereabove. An insert housing member 28 is threadedly secured at 30 to the upper end of the sleeve 22 and extends upwardly into connection at 32 with a tubular sand accumulation chamber 34. A suitable reciprocal type insert pump and housing therefor, generally indicated at 36, is suitably secured to the upper end of the accumulation chamber 34, and extends upwardly therefrom within the tubing 10. The insert housing 28 provides communication between the chamber 26 and the interior 40 of the accumulation chamber. In addition, the insert member 28 provides communication between the interior chamber 40 and the annular space 42 between the sleeve member 22 and the tubing 10, as will be hereinafter set forth.

30 The insert member 28 comprises a main housing portion 44 of substantially cylindrical configuration, and having a reduced sleeve member 46 extending downwardly within the sleeve 22. A tubular retaining sleeve member 48 is threadedly inserted in the lower end of the reduced sleeve 46 to retain a tubular valve seat member 50 and valve ball 52 therein. The ball member 52 normally rests on the valve seat member 50 in a normally closed position, as shown in the drawings. A downwardly extending stop member 54 is provided within the reduced sleeve 46 for limiting the upward movement of the ball 52. A plurality of circumferentially spaced angular bores 56 extend upwardly in the body 30 to provide communication between the interior of the sleeve 46 and the annular space 42, for a purpose as will be hereinafter set forth.

35 A plurality of circumferentially spaced longitudinal bores 58 are provided in the body 30, and are interposed between the angular bores 56 to preclude interference therebetween. The bores 58 extend upward through the body 30 to provide communication between the chamber 26 and an enlarged internal longitudinal bore 60 provided in the upper end of the body member 30. The bore 60, in turn, extends into communication with the interior chamber 40 of the accumulation chamber sleeve 34.

Operation

40 The standing valve 12 is installed at the bottom of the well casing in any suitable manner well known in the art, with the sleeve member 22, insert member 28, accumulation chamber 34 and reciprocal pump 36 extending up-

wardly therefrom, as hereinbefore set forth. The pump, generally indicated at 36, is usually reciprocated by means of a string of rods (not shown) extending downwardly in the well tubing into communication with the pump. The upstroke of the pump creates a suction or vacuum therebelow which is communicated through the accumulation chamber 34 and bores 60 and 58 to the chamber 26 adjacent the standing valve 12. The pressure within the chamber 26 is thus lowered to a pressure below the pressure present in the fluid reservoir. The pressure of the fluid in the bore 14 of the valve 12 will, therefore, act upwardly against the lower portion of the ball 20 exposed thereto for lifting the ball and opening the valve 12. The fluid will fill the chamber 26 and flow upwardly through the bores 58 into the bore 60 and will tend to fill the interior chamber 40 of the accumulation sleeve member 34. The sleeve member 34 is preferably constructed of a length in accordance with the working capacity of the pump to assure that the fluid will move upwardly within the chamber 40 a distance slightly less than the overall length thereof, thus precluding any contact of the fluid with the pump 36 itself.

The downstroke of the pump 36 will increase the pressure on the surface of the fluid within the chamber 40, thereby pushing the fluid downwardly to increase the pressure within the chamber 26. The fluid cannot flow downwardly out of the chamber 26 since the ball 20 will be forced against the seat 18 to close the valve 12. Thus, the increased pressure within the chamber 26 will be directed upwardly through the tubular member 48 and valve seat member 50 to act on the lower surface of the ball member 52 to raise it off the seat member 50 and permit the fluid to flow upwardly within the reduced sleeve member 46. The fluid in the sleeve 46 will be forced upwardly through the angular bores 56 and discharged therefrom into the annular space 42.

It will be apparent from FIG. 1 that the angular configuration of the bores 56 is so designed that the fluid is discharged therefrom into the annular space 42 in a radially outward and downward path whereby the fluid strikes the inner periphery of the casing 10 with sufficient force to maintain the interior walls of the casing clean and free of accumulations of debris and corrosion. The body member 30 is provided with an annular groove portion 62 (FIG. 2) on the outer periphery thereof adjacent the open ends of the bores 56 to facilitate the discharge of fluid therefrom. Furthermore, the downward force of the fluid discharged into the annular space 42 effects a cleaning action for the valve sealing cups 16 to preclude the collection of corrosion, and the like, thereon.

A continued reciprocation of the pump 36 will constantly move the fluid from the reservoir into the accumulation chamber 34 and downwardly out of the chamber 34 for discharge into the annulus 42. The continual movement of the fluid into the annulus will cause the fluid therein to rise to the surface of the well casing or tubing 10 to be delivered from the well for storage, or the like. At no time does the fluid, which normally contains sand and other abrasive foreign particles, come into contact with the reciprocating or working parts of the pump, thereby greatly prolonging the efficient life thereof, and reducing the maintenance required therefor.

From the foregoing, it will be apparent that the present invention provides a novel attachment for increasing the efficiency and useful life of a reciprocating type insert pump in a well bore. The novel attachment is particularly designed and constructed to move oil or fluid from a fluid reservoir into the well tubing for elevation to the surface of the well in a manner whereby the fluid is never brought into contact with the working parts of the pump, thereby precluding any abrasive action of the reciprocating members thereof due to the sand and other foreign particles present in the fluid.

The novel apparatus provides an accumulation chamber

for receiving the fluid below the pump, and thus assures that the fluid will not be moved into the pump itself. The attachment is simple and efficient in operation and durable and economical in construction.

5 Changes may be made in the combination and arrangement of parts as heretofore set forth in the specification and shown in the drawings, it being understood that any modification in the precise embodiment of the invention may be made within the scope of the following 10 claims without departing from the spirit of the invention.

We claim:

1. In combination with a well tubing having a fluid reservoir in the lower portion thereof, a standing valve disposed in the well tubing and extending into the fluid 15 reservoir, sealing means provided between the standing valve and the inner periphery of the well tubing, a reciprocating pump spaced above the valve, an insert body member interposed between the valve and the pump, an annular space provided above the sealing means and 20 between the insert body member and the well tubing, a lower chamber provided between the body member and the valve, an upper chamber provided between the body member and the pump, passageway means in the body member providing communication between the upper 25 and lower chambers, a check valve carried by the insert body, angular passageway means in the body providing communication between the lower chamber and the annular space in the open position of the check valve, said first mentioned passageway means cooperating with 30 the pump to alternately lower and increase the pressure in the lower chamber upon reciprocation of the pump, said lowered pressure causing the standing valve to open for receiving fluid from the reservoir, said fluid caused to move into the upper chamber by the lowered pressure, 35 said increased pressure acting on the fluid in the upper chamber to discharge the fluid from the lower chamber and upwardly through the check valve and angular passageway means and then downwardly into the annular space for elevation of the fluid to the surface 40 of the well tubing, and said upper chamber accumulating said well fluid during the decrease in pump pressure out of contact with the pump.

2. In combination with a well tubing having a reciprocating pump provided therein, a standing valve disposed in the lower portion of the tubing and extending downwardly into a fluid reservoir, a tubular housing member secured to the standing valve and extending upwardly therefrom to provide a lower chamber thereabove, an annular space provided between the housing member and the well tubing, an insert body member secured to the upper end of the housing member and extending downwardly therein into communication with the lower chamber, a second tubular housing member interposed between the body member and the pump to provide an upper chamber, passageway means provided 45 in the body member providing communication between the upper and lower chambers, angular passageway means provided in the body member providing communication between the lower chamber and the annular space, said reciprocating action of said pump providing for alternate opening and closing of said valve, said open position for said valve permitting well fluid to flow into the lower and upper chambers, said reciprocation of said pump acting on the fluid in the upper chamber to discharge the fluid upwardly through the angular passageway means and then downwardly into the annular space for elevation to the surface of the well tubing, said upper chamber providing an accumulation chamber for precluding contact of the well fluid with the pump during 55 the reciprocation thereof.
